UNITED STATES PATENT OFFICE.

GEORGE A. ENSIGN, OF DEFIANCE, OHIO, ASSIGNOR TO THE DEFIANCE MACHINE WORKS, OF SAME PLACE.

AUTOMATIC HOOP-STOCK EQUALIZING, LAPING, AND POINTING MACHINE.

SPECIFICATION forming part of Letters Patent No. 665,732, dated January 8, 1901.

Application filed June 5, 1900. Serial No. 19,142. (No model.)

To all whom it may concern:

Be it known that I, GEORGE A. ENSIGN, a citizen of the United States, and a resident of Defiance, in the county of Defiance and State 5 of Ohio, have invented a new and Improved Automatic Hoop-Stock Equalizing, Lapping, and Pointing Machine, of which the following is a full, clear, and exact description.

The invention relates to woodworking machinery; and its object is to provide a new and improved machine for treating the stock for wooden barrel-hoops, to automatically cut the same to uniform length, to point one end of each hoop, and to lap or bevel the other end 15 in a very simple and effective manner.

The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in all the views.

25 Figure 1 is a plan view of the improvement. Fig. 2 is a transverse section of the same on the line 2 2 in Fig. 1. Fig. 3 is a similar view of the same with the guide swung backward to show the cutter-heads. Fig. 4 is a trans- 30 verse section of the improvement on the line 4 4 in Fig. 1 with the guide swung backward to show the cutter-heads. Fig. 5 is an end view of the improvement, showing the driving-gear and belt-tightener. Fig. 6 is an en- 35 larged sectional side elevation of the device for beveling the ends of the hoop-stock. Fig. 7 is a like view of the hood for the same. Fig. 8 is a perspective view of the bed or anvil for supporting the hoop-stock while the latter is 40 being beveled or lapped. Fig. 9 is an en- 45 larged plan view of the cutter-head for pointing one end of the stock. Fig. 10 is an end view of the same. Fig. 11 is an enlarged plan view of the bed for supporting the hoop-stock 50 while it is being pointed. Fig. 12 is a side elevation of the same. Fig. 13 is a plan view of the finished hoop, and Fig. 14 is an edge view of the same.

The improved machine is mounted on a 55 suitably-constructed bed-frame A, support-

ing heads or tables B B', provided at their front ends with projections B² B³ for temporarily supporting the stocks C as the latter are successively removed by the operator from a bundle of hoop-stock contained in a 55 holder A', secured to or forming part of the bed-frame A, as indicated in Fig. 1.

The hoop-stock C, placed on the projection B³, is taken hold of by fingers D on endless sprocket-chains D', adapted to pass over 60 sprocket-wheels D² D³, of which the former is journaled loosely on a stud carried by the projection B², and the other sprocket-wheel D³ is secured on a driven shaft E, extending longitudinally and journaled in suitable bearings in the tables B B'. One outer end of the shaft E carries a pulley E', connected by a belt E² with a pulley E³ on the main shaft E⁴, provided with a pulley E⁵, connected by a belt E⁶ with other machinery for imparting a rotary motion to the shaft E⁴. The rotary motion of the latter is transmitted by the belt E² and pulley E' to the shaft E, so that the sprocket-wheels D³ are turned to impart a traveling motion to the sprocket-chains D' 65 70 75 and move a stock successively forward by the fingers D on the sprocket-chains D'. The stock carried forward by a pair of fingers D on the two oppositely-located sprocket-chains D' passes under guides F, held on the tables 80 B B', it being understood that the stocks extend with their ends upon the tops of the tables B B', the right-hand ends of the stocks abutting against a gage-plate B⁴, secured to the table B', as is plainly shown in Fig. 1. 85 The operator in placing a stock upon the projections B² B³ moves the stock longitudinally until the right-hand end abuts against the gage B⁴.

The guides F, under which the stocks pass 90 in their transverse movement through the machine, are pivoted at their rear ends at F' to the tables B B' and are provided with bolts F² for removably engaging keepers F³, carried by said tables B B', so that the guides can be 95 swung rearwardly in case it is desired to remove a stock. The stocks are also supported between the tables B B' by passing upon transverse bars G G' G², of which the bars G G' are secured to the inner ends of the tables 100

B B', while the middle bar G² is supported from the bed-frame A, the upper edges of said bars, however, being in the same horizontal plane as that of the faces of the tables 5 B B'.

When a pair of fingers D has moved a hoop-stock transversely and finally disengages said hoop-stock and leaves the latter at rest on the tables B B' and the bars G G' G², then 10 the left-hand end of this particular stock is cut off by one of the knives H' of a revoluble cutter-head H, held on a shaft H², extending longitudinally and journaled in suitable bearings on the top of the table B. On the shaft 15 H² is secured a gear-wheel H³, in mesh with a gear-wheel H⁴ on the driven shaft E, so that the rotary motion of the latter causes a like motion of the shaft H² to revolve the cutter-head H and cause one of the knives thereof 20 to cut off one end of the stock. As the other end of the stock rests against the gage B⁴ it is evident that the several stocks treated in the manner described will be all of a uniform length. 25 While the stock is at rest, as above described, and its left-hand end is cut off by the cutter-head H, its right-hand end rests on a bed or anvil I, held on the top of the table B', and while this end is thus at rest it is 30 pointed by the diverging knives J' of the cutter-head J. The bed I consists, essentially, of a fixed knife-blade I', secured to a bracket I², bolted or otherwise fastened to the table B', the side edges of the blade being tapered 35 to conform to the shape of the point to be given to the stock by the knives J'. The latter are secured to the opposite faces of arms J², integrally diverging from hubs J³, secured on a shaft J⁴, extending transversely and 40 journaled in suitable bearings on the top of the table B'.

On the shaft J⁴ is secured a bevel gear-wheel K, in mesh with a bevel gear-wheel K', secured on a longitudinally-extending shaft 45 K², likewise journaled on the table B' and connected by gear-wheels K³ K⁴ with the driven shaft E, so that when the latter is rotated, as above described, a rotary motion is given to the shafts K² J⁴ to revolve the cutter-head J 50 and to cause the knives J' thereof to cut the opposite sides of the right-hand end of the stock while the latter is at rest over the blade I' of the bed I. In order to hold this end of the stock in proper position for the knives J' to equally trim or cut the opposite sides of 55 the end, I provide the free ends of the arms J² with angular guide-arms J⁵, adjustably held on said arms by bolts J⁶ J⁶, extending through elongated slots J⁸ in the guide-arms J⁵.

As shown in Figs. 9 and 10, the guide-arms are beveled at their opposite edges, so that when the cutter-head J revolves the beveled edges engage the side edges of the stock and 60 hold the same in proper position over the bed I while the knives J' do the cutting.

From the foregoing it is evident that the

left-hand end of the stock is cut off by the cutter-head H, while at the same time the right-hand end of the stock is pointed by the cutter-head J, and as soon as this operation is completed then fingers L on transversely-traveling endless sprocket-chains L' engage the stock and move the same transversely to finally pass the ends of the stock over the inclined bed-pieces or anvils N and cause the ends to be slightly turned upward (see Fig. 6) for the knives O' of revoluble cutter-heads O to cut the top surfaces of the ends and bevel or lap the same, as will be readily understood by reference to Figs. 3, 4, and 6.

The endless sprocket-chains L' are arranged close to the inner sides of the tables B B' and said sprocket-chains pass over sprocket-wheels L² on the shaft E and over sprocket-wheels L³, journaled loosely on the rear ends of the bed-frame A, as is plainly indicated in Figs. 1, 2, and 4. Each of the cutter-heads O is preferably provided with four straight knives O', which can be easily ground or sharpened by an ordinary mechanic, it being understood that by bending the ends of the stock it is not necessary to employ beveled or spiral cutting-knives, as the straight edges of the knives cutting the bent ends of the stock will produce the desired bevel on the ends of the stock. Each cutter-head O is secured on a shaft O², journaled in suitable bearings attached to the corresponding table B or B', and on each shaft O² is a pulley O³, connected by a belt O⁴ with other machinery, so that a rotary motion is given to the said cutter-heads O at a high rate of speed.

In order to prevent chips or shavings cut by the knives O' from the ends of the stock from flying forward toward the operator, I provide hoods P, secured by bolts to the bearings for the shaft O². The said hoods P are arranged at the front of the cutter-heads, so that the chips or shavings are thrown rearward, and consequently do not annoy the operator feeding the stock successively to the machine, as above described. The hoods P are made very heavy and extend with their base portions over the stock ends to assist in holding the stock ends down over the bed-pieces N at the front ends thereof, while the knives O' of the cutter-heads lap or bevel the top faces of the stock ends, the bolts P' P² for the said hoods permitting the latter to yield vertically to compensate for the varying thickness of the ends of the stock.

The front and rear edges of the bed-pieces N are beveled, as illustrated in Fig. 8, so that the ends of the stock readily travel up and down the side edges upon passing to and from the said bed-pieces N, it being understood that the ends of the stock readily turn up to conform to the shape of the bed-pieces, owing to the adjacent guides F extending over the stock directly above the inner edges of the tables B B' and close to the supporting-bars G G', as will be readily understood by reference to Figs. 6 and 7.

The table B' is preferably fixed on the bed-frame A, while the table B is mounted to slide longitudinally thereon to adjust the machine for different lengths of hoop-stock, and for this purpose the table B is mounted to slide on a frame and is provided with a shaft Q, carrying at its outer end a crank-arm Q' and at its inner end a gear-wheel Q², in mesh with a rack Q³, extending longitudinally on the bed-frame A, as is plainly indicated in Figs. 2 and 3.

In order to stop or start the machine, I prefer to use a loose belt E² and a belt-tightener for the same, as illustrated in Fig. 5, said belt E² when tight driving the pulley E' and when loose preventing rotation of said pulley. The belt-tightener consists, essentially, of a tightener-pulley R, adapted to engage the lower run of the belt E², adjacent to the pulley E', and this tightener-pulley R is journaled in a lever R', fulcrumed at R² and having an opening R³ at its outer end for engagement by a rod R⁴, extending in front of the machine and connected with a lever R⁵, fulcrumed on the bed-frame and adapted to be pushed to one side by the operator handling the stock, as previously explained. When the rod R⁴ is in engagement with the lever R', then the pulley R tightens the belt E²; but when the operator pushes the lever R⁵ to the right then the rod R⁴ is withdrawn from the lever R' and the pulley R can now swing by its own weight out of engagement with the belt E², so that the latter comes to a stop and with it the pulley E' and shaft E. The swinging motion of the lever R' is limited by a bolt R⁶, secured to the end of the bed-frame and extending through an elongated slot R⁷, formed on the lever R'. (See Fig. 5.)

The operation is as follows: When the shafts E and O² are rotated, as previously explained, and the operator places a stock on the projections B²B³, with the right-hand end of the stock abutting against the gage B⁴, then a pair of fingers D will take hold of the stock and move the same transversely over the supporting-bars G G' G² and the tables B B' until the stock is moved with the right-hand end upon the bed I, and then the fingers disengage the stock and one of the knives H' now cuts off the left-hand end of the stock, while the right-hand end is trimmed at opposite sides by the cutter-head J to point this end of the stock. As soon as this has been done a pair of fingers L engage the stock and move the same farther transversely and over the bed-pieces N to bend the ends of the stock upward, so that the cutter-heads O bevel the ends of the stock, as above explained. The fingers L carry the stock farther forward and finally drop the same when the fingers pass around the wheels L³. It is understood that the operator feeds the stock successively to the machine, as above described, it being understood that the succeeding pairs of fingers D first move the stock a short distance, and

then after the stock has been equalized by the cutter-head H and pointed by the cutter-head J it is again moved forward by the fingers L of the endless traveling chains L'. 70

From the foregoing it is evident that no reciprocating cutter-heads are employed, as in machines heretofore constructed and used for the same purpose, and, furthermore, no spiral cutter-heads are necessary, as the cutter-heads O have straight knives, so that an ordinary mechanic can readily sharpen the knives and in general attend to the machine without employing skilled labor. 75

Having thus fully described my invention, 80 I claim as new and desire to secure by Letters Patent—

1. A machine of the class described, provided with a revoluble cut-off cutter-head for cutting off one end of a hoop-stock while the latter is at rest, a revoluble pointing cutter-head for pointing the other end of the hoop-stock, a pair of revoluble lapping cutter-heads for beveling or lapping the ends of the hoop-stock, and carriers moving in unison for intermittently moving the hoop-stock forward, the first carrier moving the hoop-stock to position for the cut-off cutter-head and the pointing cutter-head to act on the hoop-stock while the latter is at rest, and the second carrier 90 moving the hoop-stock, after being cut off and pointed, forward and past the lapping cutter-heads for beveling the ends of the hoop-stock, as set forth.

2. In a machine of the class described, a 100 revoluble pointing cutter-head having diverging arms provided with knives, and angular centering-guides adjustable on said diverging arms, as set forth.

3. In a machine of the class described, a 105 revoluble pointing cutter-head having diverging arms provided with knives, angular centering-guides adjustable on said arms, and a bed having a blade with side edges operating in conjunction with said knives, to point the 110 end of the hoop-stock, as set forth.

4. A machine of the class described, having a revoluble pointing cutter-head comprising hubs and arms diverging from said hubs and provided with knives, a bed having a 115 blade with side edges operating in conjunction with the knives to point the end of the hoop-stock, centering-guides on said arms for centering the end of the hoop-stock and holding it against lateral movement while the 120 knives cut the end of the stock, and a carrier for moving the hoop-stock in position, as set forth.

5. A machine of the class described, provided with a gage or abutment for one end of 125 the hoop-stock, a revoluble cutter-head for cutting off the other end of the hoop-stock, a pointing cutter-head adjacent to the said gage and arranged to point the end of the hoop-stock after it leaves the gage, the said 130 pointing cutter-head having diverging arms provided with knives, and centering-guides

adjustable on said arms, and a carrier for moving the hoop-stock in position to be acted on by the said cutter-heads, as set forth.

6. In a machine of the class described, a carrier for moving a hoop-stock forward, supporting-bars for the hoop-stock, guides under which the ends of the hoop-stock pass, a pair of revoluble lapping cutter-heads for beveling the ends of the hoop-stock, a bed below each cutter-head and having a beveled surface for holding the ends of the hoop-stock at an angle to the cutting-line of said cutter-head, and hoods for the cutter-heads and having their base portions extending over the stock ends to hold the stock ends down over the beds, the said hoods being weighted and mounted to yield vertically, as set forth.

7. In a machine of the class described, a carrier for moving a hoop-stock forward, a pair of revoluble lapping cutter-heads for beveling the ends of the hoop-stock, guides extending over the stock and engaging the same adjacent to the ends to be beveled, a bed below each cutter-head and having an inclined surface for holding the end of the hoop-stock at an angle to the cutting-line of said cutter-head, the said beds having the hoop-stock entrance edge beveled to gradually bend the ends of the hoop-stock, the exit edge of the bed being also beveled to allow the stock to straighten out after leaving the inclined surface of the bed, and means engaging and bearing on the ends of the hoop-stock, while the cutter-heads cut said ends, substantially as set forth.

8. A machine of the class described, provided with a pointing cutter-head, comprising a revoluble shaft, diverging arms secured to the shaft, knives secured to opposite sides of the arms, and adjustable centering-guides on the said arms, substantially as shown and described.

9. A machine of the class described, provided with a pointing cutter-head, comprising a revoluble shaft, hubs secured on said shaft, arms diverging from said hubs, knives secured to the inner sides of the arms, and angular guides provided with elongated slots and adjustably held on the said arms, substantially as described.

10. A machine of the class described provided with a bed having a blade with tapering side edges, and a pointing cutter-head comprising a revoluble shaft, diverging arms secured to said shaft, knives secured to opposing sides of the arms and acting in conjunction with the blade on said bed, and adjustable centering-guides on the said arms, substantially as described.

11. A machine of the class described, provided with tables, carriers operating in unison for moving a hoop-stock intermittently, guides under which the hoop-stock passes, the said guides being pivoted at their rear ends to the tables, and bolts carried by said guides for removably engaging keepers carried by said tables for the purpose set forth.

12. In a machine of the class described, a shaft mounted to turn, means for driving the same, an endless carrier driven from said shaft and adapted to carry the hoop-stock forward, a gage or abutment for one end of the hoop-stock and located at one side of the carrier, a revoluble cutter-head located at the opposite side of the carrier for cutting off the projecting end of the hoop-stock, a pointing cutter-head located adjacent to the gage for pointing the end of the hoop-stock, the said cutter-heads being driven from the shaft, lapping cutter-heads for beveling the ends of the hoop-stock, and a second carrier driven from the said shaft and moving in unison with the first carrier for moving the hoop-stock to said lapping cutters after its ends are cut and pointed, substantially as set forth.

13. A machine of the class described, comprising a shaft mounted to turn, means for driving the same, an endless carrier for feeding the hoop-stock forward and driven from said shaft, a cutter-head located at one side of the carrier for cutting off one end of the hoop-stock, a pointing cutter-head for pointing the other end of said hoop-stock, the said cutter-heads being driven from the shaft, a second carrier driven from the said shaft for feeding the hoop-stock forward after its ends are cut and pointed respectively, and lapping cutter-heads located at opposite sides of the said second carrier for beveling the ends of the hoop-stock, substantially as described.

14. A machine of the class described, comprising a bed-frame, tables supported on said bed-frame and provided at their front ends with projections for temporarily supporting the hoop-stocks, a shaft mounted to turn in bearings in the tables near the front thereof, an endless carrier driven from said shaft and comprising oppositely-located sprocket-chains provided with fingers and passing over sprocket-wheels, a gage-plate at one side of the carrier and secured to one of said tables, and against which one end of the hoop-stock abuts, a pointing cutter-head journaled adjacent to the gage and arranged to point the end of the hoop-stock, a revoluble cutter-head carried by the other table and located at the opposite side of the carrier and arranged to cut off the projecting end of the stock, the said carrier moving the hoop-stock to position to be cut off and pointed, a second carrier driven from the said shaft and comprising oppositely-located sprocket-chains arranged near the inner sides of the tables and passing over sprocket-wheels, the said chains being provided with fingers arranged to engage and move the hoop-stock after the latter is cut off and pointed, and cutter-heads carried by the said tables and located at opposite sides of the said second carrier for beveling or lapping the ends of the hoop-stock, substantially as described.

15. A machine of the class described, comprising a bed-frame, tables supported on said bed-frame, one of said tables being adjust-

able on said bed-frame toward and from the other table, means for adjusting said table, and carriers located adjacent to the inner sides of the tables and operating in unison for moving a hoop-stock intermittently, as set forth.

16. A machine of the class described, comprising a bed-frame, tables supported on said bed-frame, one of said tables being adjustable on said bed-frame toward and from the other table, carriers located adjacent to the inner sides of said tables and operating in unison for moving the hoop-stock intermittently, a revolute cut-off cutter-head carried 10 by one of said tables for cutting off one end

of a hoop-stock, while the latter is at rest, a revolute pointing cutter-head carried by the other table for pointing the other end of the hoop-stock, and a revolute lapping cutter-head carried by each of said tables for beveling or lapping the ends of the hoop-stock, as set forth. 20

In testimony whereof I have signed my name to this specification in the presence of two subscribing witnesses.
